UNITED STATES PATENT OFFICE.

CARL OTTO THIEME, OF ST. LOUIS, MISSOURI.

DEVICE FOR CUTTING BOILER-TUBES.

SPECIFICATION forming part of Letters Patent No. 531,662, dated January 1, 1895.

Application filed October 1, 1894; Serial No. 524,582. (No model.)

To all whom it may concern:

Be it known that I, CARL OTTO THIEME, of the city of St. Louis, State of Missouri, have invented certain new and useful Improvements in Devices for Cutting Boiler-Tubes, of which the following is a full, clear, and exact description, reference being had to the accompanying drawings, forming a part hereof.

My invention has relation to improvements in devices for cutting boiler tubes and consists in the novel arrangement and combination of parts more fully set forth in the specification and pointed out in the claims.

In the drawings, Figure 1 is a middle longitudinal section of my invention applied to a boiler tube. Fig. 2 is a section on line *a a* of Fig. 1. Fig. 3 is a section on line *b b* of Fig. 1. Fig. 4 is a detail view of one of the cutters. Fig. 5 is an end view of the base of 20 the cone controlling the cutters. Fig. 6 is a detached view of a second form of cutter. Fig. 7 is a middle vertical section of the rocker as hereinafter explained. Fig. 8 is a section on line *c c* of Fig. 7; and Fig. 9 is an enlarged side view of the inner end of the sleeve surrounding the main shaft of my device.

The object of my invention is to materially simplify the construction set forth and described in Letters Patent No. 512,631, granted to me under date of January 9, 1894, and to this end I have devised a boiler tube cutter which in detail may be described as follows:

Referring to the drawings, 1 indicates the boiler head or sheet from which the tube 2 extends and to which the end of the tube is secured.

3 indicates a shaft screw-threaded at one end, on which operates a hand disk 4 limited outwardly by the terminal head 5 at the outer end of the screw-threaded portion. Over the inner reduced stem 6 of the shaft 3 is passed a cone 7, the narrow end of the cone resting against the inner end of the shaft 3, the cone being held on the stem by the terminal nut 8. The outer surface of the cone is provided with a series of converging peripheral dovetail guides 9 and guide-ways 10, the purpose of which will hereinafter be explained.

Surrounding the shaft 3 is a sleeve 11, the inner end of which is provided with an enlarged portion or hollow head 12 whose inner walls are conical for the accommodation of

the cone 7. About the sleeve 11 is free to move a rotatable conical exteriorly-screw-threaded casting 13 whose inner reduced end 55 is limited by the circular shoulder 14 formed at the base of the portion 12.

The outer peripheral edge of the casting is provided with a series of depressions or notches 15 for the engagement of the ends of 60 the rocker 16 hereinafter to be described.

Mounted loosely on the sleeve 11 exterior and adjacent to the casting 13 is a forked handle 17. Between the forks 18 of the handle and fixed to the sleeve 11 is a ratchet 65 wheel 19 engaged by the pawl 20 pivoted by a bolt 21 between the forks.

Mounted on the side of the handle on the fork adjacent to the casting 13 is a rocker 16 having engaging ends 22. The rocker swings 70 or depends from the smooth end of a securing bolt 23. This end of the bolt is provided with two adjacent flat surfaces 24 making an obtuse angle with each other. Within the rocker is a longitudinal cavity or socket 25 in which 75 is inserted a pin 26 whose head is adapted to contact with either of the surfaces 24, the said pin pressing against the surfaces 24 by the action of the encircling spring 27 confined between the bottom of the cavity 25 and the head 80 of the pin. Before the rocker is mounted on the bolt 23 the pin 26 is first passed into its cavity through the opening 28 in the rocker, and when the parts are adjusted the rocker is passed over the bolt and secured as best shown 85 in Figs. 1 and 3. It is obvious that if the rocker be tilted in the position as shown in Fig. 3, one of the surfaces 24 will come in contact with the head of the pin 26, the encircling spring 27 keeping it in that position—a position 90 by which one of the engaging ends 22 is enabled to engage with the depressions 15 of the rotatable casting 13, and thus upon rotation of the handle 17 turn the casting 13 in one direction and screw the same firmly into 95 the end of the tube 2 (it being understood that the rocker will engage the depressions 15 and turn the casting 13 as the handle 17 is operated in one direction, and slide past the depressions upon the return stroke of the handle).

When the rocker is tilted in the opposite direction so as to bring the second surface 24 in contact with the head of the pin 26, the opposite engaging end 22 of the rocker

will engage the depressions 15, and by a reverse operation of the handle 17 unscrew the casting 13 from out of the tube 2.

The opposite guides 9 receive the cutters 30, the bases of which have corresponding dove-tail openings 31 to pass over the guides, and the guide-ways 10 receive the cutters 32 whose bases have dove-tail projections 33 to enter said guides. This arrangement makes the most perfect and durable form of cutting device. The outer ends of the cutters pass through cut-away portions 34 formed along the inner periphery of the enlarged portion 12, the end of this portion being interiorly screw-threaded as at 35, and into this is screwed the casing 36, the distance to which it is screwed being limited by the shoulder 37 at the base of the screw-threaded portion 35. The casing is screwed by the aid of the polygonal nut or head 38. When the casing 36 is driven home the screw-threaded end thereof just reaches to the cutters, and thus guides the latter as they pass through the openings 34, preventing lateral binding.

25 The operation is as follows: After the parts are assembled as indicated, the casting 13 is driven into the tube 2 as already indicated (it being understood of course that during the rotation of the casting the pawl 20 is disengaged from the ratchet 19). Then, upon the turning of the hand disk 4 in the proper direction the shaft 3 with its cone 7 will be drawn outwardly, the guides 9 and guide-ways 10 forcing outwardly, that is, expanding 35 the cutters against the inner wall of the tube 2. The rocker 16 is then disengaged or tripped so as to slide by the depressions 15, the pawl 20 is thrown into engagement with the ratchet 19, the handle 17 is then operated in proper 40 direction to turn the ratchet, which in turn imparts a rotary motion to the sleeve 11, this operating the cutters at the inner end thereof. The said cutters are kept in contact with the inner wall of the tube 2 by operating the 45 hand disk 4 in proper direction, it being remembered that this disk moves the shaft 3 which expands the cutters when moved outwardly. The casing 36 thoroughly protects the inner parts of the device, and at the same 50 time its end where it meets the enlarged portion 12 serves as a guide for the cutters 30 and 32.

Having described my invention, what I claim is—

55 1. In a tube cutter, a suitable screw-threaded shaft, a cone at the inner end thereof, a sleeve embracing said shaft, cut-a-way portions at the inner end of said sleeve, a casing

detachably secured to the inner enlarged end of the sleeve, suitable guides and guide-ways 60 on the periphery of the cone, cutters passing through the cut-a-way portions, means for rotating the sleeve and expanding the cutters, substantially as set forth.

2. In a tube cutter, a suitable shaft, a sleeve 65 surrounding the same, a rotatable exteriorly screw-threaded casting passed over said sleeve, an operating handle embracing said sleeve, a series of peripheral depressions along the outer edge of the casting, a rocker pivoted to the handle, and means for giving a predetermined inclination to the rocker, substantially as set forth.

3. In a tube cutter, a suitable sleeve, a rotatable casting surrounding the same, a handle embracing the sleeve, a rocker pivoted to the side of the handle, a retaining bolt for said rocker having a smooth end and flat surfaces contiguous to one another and at a suitable angle with each other, a cavity in said 80 rocker, a pin in said cavity having a head co-operating with the flat surfaces of the bolt, and an encircling spring for said pin to keep the same in contact against either of the flat surfaces of the retaining bolt, substantially 85 as set forth.

4. In a tube cutter, a suitable shaft, a sleeve embracing the same, an enlarged inner end on said sleeve, suitable cut-a-way portions at the end of the enlarged portion of the sleeve, 90 said enlarged end being interiorly screw-threaded and having a limiting shoulder or ridge at the base of the screw-threaded portion, and a casing adapted to screw into the enlarged end of the sleeve and limited by the 95 said shoulder, a series of cutters at the inner end of the shaft, said cutters passing through the cut-a-way openings and being guided by the end of the casing, substantially as set forth.

5. In a tube cutter, a suitable screw-threaded shaft, a cone at the inner end thereof, a sleeve embracing said shaft, cut-a-way portions at the inner end of the sleeve, a casing 105 detachably secured to the inner enlarged end of the sleeve, suitable dove-tail guides and guide-ways on the periphery of the cone, cutters passing through the cut-a-way portions, and means for rotating the sleeve and expanding the cutters, substantially as set forth.

In testimony whereof I affix my signature in the presence of two witnesses.

CARL OTTO THIEME.
